UNITED STATES PATENT OFFICE.

ANTHONY M. WARTHMAN, JR., OF PHILADELPHIA, PENNSYLVANIA, ASSIGNOR
TO A. H. WARTHMAN, CHARLES H. WARTHMAN, AND ANTHONY M. WARTH-
MAN, JR., OF SAME PLACE.

IMPROVEMENT IN APPARATUS FOR COOLING LARD.

Specification forming part of Letters Patent No. **151,941**, dated June 9, 1874; application filed
February 21, 1874.

To all whom it may concern:

Be it known that I, ANTHONY M. WARTHMAN, Jr., of Philadelphia, Pennsylvania, have invented certain Improvements in Apparatus for Cooling Lard, of which the following is a specification:

The object of my invention is to rapidly cool rendered lard, and reduce it to a condition in which it can be packed for transportation and sale; and this object I attain by the apparatus shown in the vertical section, Figure 1, and transverse vertical section, Fig. 2, of the accompanying drawing, which I will now proceed to describe.

To the joists *a* of a building are suspended ways or rails *b*, for receiving the flanged wheels *d* on axles fixed to the frame *B*, so that the latter can be reciprocated on the rail by a crank, *E*, and pitman *F*, as shown in Fig. 1. Four guiding-hangers, *e*, project downward from the frame *B*, and to vertical grooves in these hangers are adapted the corner posts *f* of the frame *A*, consisting of the said posts *f* and a number of intermediate posts, *f'*, all properly secured together and stayed by diagonal ties *m*. From each post on one side of the frame *A* to the corresponding post on the opposite side of the said frame extend a number of slats, *n*, two posts and their slats forming a dasher, *M*. In the present instance there are five of these dashers; but they may be more or less in number, according to the size of the trough *D'*. From each end of the frame *A* extends a rope or chain, *h*, over a pulley, *i*, on a hanger secured to the frame *B*, the two ropes being connected to a cross-shaft, *p*, adapted to bearings in the said frame *B*, so that, by turning this shaft, the frame *A* may be raised or lowered at pleasure. The exterior trough *D* may be made of wood; but the inner trough *D'* should be made of thin metal, by preference sheet-zinc or galvanized sheet-iron, the said inner trough resting on slats in the bottom of the outer trough, as shown in Fig. 2. Cold water is permitted to circulate freely between the two troughs, and, when circumstances permit, it is preferable for the drainage of an ice-house to

be admitted to the space between the troughs; or ice-water can be used.

When the apparatus has to be put in operation, the frame *A* is lowered until projections on the top of the corner posts catch against projections at the lower ends of the hangers *e*, as shown in the drawing, when the frame *B* is entirely supported by the said hangers, and the lower edges of the dashers are as near as possible to the bottom of the inner trough without being in absolute contact therewith. The hot rendered lard is now deposited in the metal trough, and the crank *E* is caused to revolve, thereby imparting a reciprocating motion to the frame *B*, as well as to the frame *A* and its dashers. The shaft to which the crank *E* is attached should be provided with such appliances, or should be so driven from another shaft, that its speed may be increased or diminished at pleasure. When the lard is first introduced into the trough, and is in a very fluid condition owing to its heat, the reciprocating motion of the dashers should be comparatively slow, so as to prevent lard from escaping from the trough under the agitation caused by the dashers. As the lard commences to become thick and this danger ceases, the speed of the reciprocating dashers may be increased, and when the lard becomes properly cooled, and of the desired consistency, the frame *A*, with its dashers, may be elevated clear of the trough, so that the lard may be removed therefrom preparatory to being packed for transportation and storage.

I have found that by thus agitating the lard in a metal vessel around which water can circulate freely, not only is the cooling operation facilitated, but the lard is superior, as regards clearness, to that which has been cooled in the ordinary manner.

I do not claim, broadly, a lard-cooling apparatus in which the dashers are adjustable, as they have heretofore been hinged to the frames so as to be separately turned up out of the lard; but

I claim—

1. The combination, in a lard-cooling appa-
